(57) **CLAIM**

The ornamental design for a keyboard, as shown and described.

DESCRIPTION

FIG. 1 is a front and top perspective view of a keyboard, showing my new design;

FIG. 2 is a rear and top perspective view thereof;

FIG. 3 is a left and top perspective view thereof;

FIG. 4 is a front elevation view thereof;

FIG. 5 is a rear view thereof;

FIG. 6 is a left side elevation view thereof;

FIG. 7 is a right side elevation view thereof;

FIG. 8 is a top plan view thereof;

FIG. 9 is a bottom plan view thereof; and,

FIG. 10 is an enlarged view of the portion, labeled '10' of FIG. 3.

The evenly spaced dashed broken lines depict portions of the keyboard that form no part of the claimed design. The dot-dash line circles depict the limits of the enlarged views and form no part of the claimed design.
